US0D1092214S

(12) **United States Design Patent** (10) **Patent No.:** **US D1,092,214 S**
(45) **Date of Patent:** **** Sep. 9, 2025**

(54) **HEAT TRANSFER PACKING ELEMENT**

(71) Applicant: **Knight Material Technologies LLC**,
Canton, OH (US)

(72) Inventors: **Izak Nieuwoudt**, Canton, OH (US);
Karl-Heinz Schofalvi, Canton, OH
(US)

(73) Assignee: **KNIGHT MATERIAL
TECHNOLOGIES LLC**, Canton, OH
(US)

(**) Term: **15 Years**

(21) Appl. No.: **29/987,427**

(22) Filed: **Jan. 23, 2025**

Related U.S. Application Data

(63) Continuation of application No. 29/921,541, filed on Dec. 18, 2023, now Pat. No. Des. 1,066,020, which is a continuation of application No. 29/816,813, filed on Nov. 24, 2021, now Pat. No. Des. 1,013,510.

(57) **CLAIM**

The ornamental design for a heat transfer packing element, as shown and described.

DESCRIPTION

FIG. 1 shows a front perspective of a heat transfer packing element showing our new design;

FIG. 2 shows a front elevation view thereof;

FIG. 3 shows a rear elevation view thereof;

FIG. 4 shows a right elevation view thereof;

FIG. 5 shows a left elevation view thereof;

FIG. 6 shows a top plan thereof; and,

FIG. 7 shows a bottom plan thereof.

The broken lines in the accompanying drawings illustrate portions of the heat transfer packing element that form no part of the claimed design.

1 Claim, 5 Drawing Sheets
